(57) **CLAIM**

The ornamental design for a knife handle, as shown and described.

DESCRIPTION

FIG. 1 is a left side elevational view of the design of the present invention for a knife handle for a folding knife showing the knife in an extended position, with the knife blade depicted in phantom lines which forms no part of the claimed design for this invention;

FIG. 2 is a right side elevational view of the knife handle of FIG. 1;

FIG. 3 is a front elevational view of the knife handle of FIG. 1;

FIG. 4 is a rear elevational view of the knife handle of FIG. 1;

FIG. 5 is a top plan view of the knife handle of FIG. 1; FIG. 6 is a bottom plan view of the knife handle of FIG. 1; and,

FIG. 7 is a left side elevational view, similar to FIG. 1, of the knife handle of the folding knife showing the knife in a stowed position.

The broken lines shown are for illustrative purposes only and form no part of the claimed design.
